UNITED STATES PATENT OFFICE.

SEVERINO DANNOLFO, OF SOUTH BARRE, MASSACHUSETTS.

DESIGN FOR A LADY'S SHOE.

61,087.

Specification for Design.

Patented June 20, 1922.

Application filed March 10, 1920. Serial No. 364,873. Term of patent 14 years.

To all whom it may concern:

Be it known that I, SEVERINO DANNOLFO, a subject of the King of Italy, residing at South Barre, in the county of Worcester and State of Massachusetts, have invented a new, original, and ornamental Design for a Lady's Shoe, of which the following is a specification, reference being had to the accompanying drawings, forming part thereof.

In the drawing the view is a side elevation of a shoe embodying my new design.

I claim:

The ornamental design for a lady's shoe as shown.

SEVERINO DANNOLFO.
